VACUUM FORMING MACHINE

John C. Kreitz, Minneapolis, Minn., assignor to Production Products, Inc., Minneapolis, Minn., a corporation of Minnesota

Filed Sept. 26, 1966, Ser. No. 4,044

Term of patent 14 years

(Cl. D55—1)

FIG. 2

FIG. 2

FIG. 3

FIG. 4

FIG. 4

FIG. 5

FIG. 5

FIG. 1 is a front perspective view of a vacuum forming machine showing my new design;

FIG. 2 is a rear perspective view thereof;

FIG. 3 is a top plan view thereof;

FIG. 4 is a view thereof of one side in elevation, the other side being identical thereto;

FIG. 5 is a front view in elevation thereof; and

FIG. 6 is a rear view in elevation thereof.

I claim:

The ornamental design for a vacuum forming machine, as shown and described.
